UNITED STATES PATENT OFFICE.

SIMON REINNSBERG, OF QUINCY, ILLINOIS.

DESIGN FOR A CREAM-SEPARATOR.

SPECIFICATION forming part of Design No. 30,741, dated May 9, 1899.

Application filed April 12, 1899. Serial No. 712,811. Term of patent 7 years.

To all whom it may concern:

Be it known that I, SIMON REINNSBERG, a citizen of the United States, residing at Quincy, in the county of Adams and State of Illinois, 5 have invented and produced a new and original Design for a Cream-Separator, of which the following is a specification.

The invention relates to a new and original design for cream-separators.

10 The principal feature of my design consists in a cream-separator having a conical top, a circular base, and a round stem connecting the top and base, and a minor feature of the design resides in the arrangement of the perforations at the base around the stem.

15 The figure of the drawing is a perspective view of a cream-separator, showing my design.

Referring to the drawing, 1 designates the base of the cream-separator, which base is 20 circular in plan view and provided at its upper face with perforations 2, arranged in an annular series around the stem 3, which is located at the center of the base. The stem 3 is round, and the top 4, which is located at the upper end of the stem, is of inverted conical 25 shape and its sides incline upward and outward from the upper end of the stem. The stem is vertical and the base has its upper face arranged in a horizontal plane, and its sides, which are cylindrical, are disposed vertically.

What I claim is—

The design for a cream-separator herein shown and described.

In testimony that I claim the foregoing as 35 my own I have hereto affixed my signature in the presence of two witnesses.

SIMON REINNSBERG.
